(57) **CLAIM**

The ornamental design for tab for a tamper-evident container, as shown and described.

DESCRIPTION

FIG. 1 is a perspective view of tab for a tamper-evident container of our design;

FIG. 2 is a perspective view of tab for the tamper-evident container of FIG. 1, shown in an open position;

FIG. 3 is a back view of tab for the tamper-evident container of FIG. 1;

FIG. 4 is a front view of tab for the tamper-evident container of FIG. 1;

FIG. 5 is a side view of tab for the tamper-evident container of FIG. 1;

FIG. 6 is a side view of tab for the tamper-evident container of FIG. 1;

FIG. 7 is a top view of tab for the tamper-evident container of FIG. 1; and,

FIG. 8 is a bottom view of tab for the tamper-evident container of FIG. 1.

1 Claim, 8 Drawing Sheets
